CLAIM

The ornamental design for a transformer power supply for a gas discharge lamp, as shown and described.

DESCRIPTION

FIG. 1 is a perspective view of a transformer power supply for a gas discharge lamp, showing our new design.

FIG. 2 is elevation view of one end thereof, the elevation view of the opposite end being identical.

FIG. 3 is an elevation view of one side thereof, the elevation view of the opposite side being identical.

FIG. 4 is a top plan view thereof.

FIG. 5 is a bottom plan view thereof; and,

FIG. 6 is another perspective view thereof.

The phantom lines illustrate environment and form no part of the claimed design.
